United States Patent Office

Des. 219,366
Patented Dec. 8, 1970

219,366

BOTTLE

Dan Lewis, Jr., Champaign, Ill., and Harold Robert Day,
Cincinnati, Ohio, assignors to National Distillers and
Chemical Corporation, New York, N.Y., a corporation
of Virginia

Filed June 26, 1969, Ser. No. 17,893

Term of patent 14 years

Int. Cl. D9—01

U.S. Cl. D9—46

FIG. 1.

FIG. 2.

FIG. 1 is a side elevational view of a bottle showing our new design;

FIG. 2 is a side elevational view looking from the right of FIG. 1;

FIG. 3 is a top plan view;

FIG. 4 is a side elevational view showing the side opposite to that seen in FIG. 1;

FIG. 5 is a top plan view of another embodiment of our new design having a modified finish and showing the handle in the down position;

FIG. 6 is a fragmentary side elevational view showing the upper portion of the bottle of FIG. 5, it being understood that the portions not shown are the same in appearance as the respective portions of the bottle of FIGS. 1, 2, 3 and 4; and

FIG. 7 is a side elevational view looking from the right of FIG. 6.

We claim:

The ornamental design for a bottle, as shown and described.
